(57) **CLAIM**

The ornamental design for a LED recessed light apparatus, as shown and described.

DESCRIPTION

FIG. 1 is a top perspective view of a LED recessed light apparatus showing our design;

FIG. 2 is a bottom perspective view thereof;

FIG. 3 is a front side view thereof;

FIG. 4 is a back side view thereof;

FIG. 5 is another side view thereof;

FIG. 6 is an opposing side view thereof;

FIG. 7 is a top view thereof;

FIG. 8 is a bottom view thereof;

FIG. 9 is a top perspective view of a LED recessed light apparatus showing our design;

FIG. 10 is a bottom perspective view thereof;

FIG. 11 is a front side view thereof;

FIG. 12 is a back side view thereof;

FIG. 13 is another side view thereof;

FIG. 14 is an opposing side view thereof;

FIG. 15 is a top view thereof; and,

FIG. 16 is a bottom view thereof.

The broken lines shown herein are for illustrative purposes only and form no part of the claimed design. The illustrated device is not limited to the scale shown.
